UNITED STATES PATENT OFFICE.

LOUIS H. MAYVILLE, OF GRANITE HEIGHTS, WISCONSIN.

RAIL BRACE.

Application filed January 8, 1923. Serial No. 611,341.

To all whom it may concern:

Be it known that I, LOUIS H. MAYVILLE, a citizen of the United States, residing at Granite Heights, in the county of Marathon 5 and State of Wisconsin, have invented new and useful Improvements in Rail Braces, of which the following is a specification.

The object of this invention is to produce a simple, cheaply constructed but thoroughly efficient means for holding the rails of a railway track against tilting in an opposite direction and for sustaining such rails in proper alignment.

To the attainment of the foregoing and other objects which will present themselves as the nature of the invention is better understood, reference is to be had to the drawings which accompany and which form part of this application.

20 In the drawings:—

Figure 1 is a plan view showing a rail supported against outward movement and against tilting in accordance with this invention.

25 Figure 2 is a sectional view on the line 2—2 of Figure 1.

Figure 3 is a sectional view on the line 3—3 of Figure 1.

30 Figure 4 is a perspective view of the member constituting the improvement.

Figure 5 is a similar view but illustrating a slight modification.

35 Figure 6 is a sectional view similar to Figure 2, but illustrating the application of the construction illustrated in Figure 5.

In the drawings the numerals 1 and 2 designate railway rails which rest on and are spiked to ties 3.

40 My improved rail braces are designed for contacting engagement with both of the rails 1 and 2, but the said braces are not ordinarily arranged opposite each other. Each of the rail braces includes an angle block 4 whose upper end is cut angularly, as at 5. The blocks are of a length whereby the angle ends 5 thereof will underlie the head of a rail and will contact with the outer edge of the base flange of such rail. To more effectively compensate for this latter engagement the lower edges of the blocks 45 are channeled, as at 6, the walls of which

correspond with the rounded outer edges of the base flanges of the rails. Each block 4 is gradually widened from its top to its bottom, its said widened bottom being formed 55 on a base plate 7 which extends outwardly and laterally in one direction from the block. The base plate 7 has an opening for a spike 8 that enters the tie 3. The laterally extending portion of the base plate 7 is, for 60 distinction, indicated by the numeral 9, the same having a downturned flange 10 disposed in contacting engagement with a side of the tie 3, the said flange being formed with a plate extension 11 having openings 65 for spikes 13 that are driven into the side of the tie.

With a construction as above described it will be apparent that outward bodily movement of the rails on their ties as well as outward tilting of said rails will be effectively 70 prevented. To hold the rails from inward movement there may pass through suitable bolt openings in the webs of the rails and similar openings in the heads 4 of the brace 75 members bolts 14 engaged by nuts 15, but under ordinary conditions this last mentioned arrangement will not be found necessary.

In Figure 5 of the drawings, I have illustrated a slight modification. In the main the brace is similar to that above described except that the plate 17 formed on the flange 18 of the head extension is notched, as at 19 or is otherwise provided with an 80 upstanding lug, the distance between the shoulder provided by the inner end of the flange 17 and the said lug being equal to the width of the base flange of the rail and in this manner the rail brace is provided with a 85 pocket for the base flange of the rail.

Having described the invention, I claim:—

The combination with railway rails and ties on which the rails rest and to which the 95 rails are spiked, of brace members for the outer sides of the rails, each including a plate resting on a tie, spiked thereto and having its inner edge in contacting engagement with the outer edge of the base flange 100 of the rail, said plate having a downturned flange formed with a longitudinal extension

which rests against and is spiked to the side of the tie, said plate having formed therewith an upwardly extending inwardly inclined block which decreases in thickness from its juncture with the plate to its outer edge and whose inner and lower edge is channeled to provide a pocket for the edge of the base flange of the rail, and whose re-

duced outer end is cut at an angle to receive the head of the rail thereon and to contact with the web of the rail at the juncture of its head therewith, and removable connecting means between the block and the web of the rail.

In testimony whereof I affix my signature.
LOUIS H. MAYVILLE.
